STORAGE TUBE

Richard L. Snyder, Jr., New York, N. Y., assignor
to Radio Corporation of America, a corporation
of Delaware

Application April 12, 1946, Serial No. 661,684

13 Claims. (Cl. 250—150)

1 This invention relates to cathode ray tubes and is particularly useful in storage tubes such as disclosed in my application filed July 24, 1945, Serial No. 606,812, though it is not limited thereto since it can be applied to various types of tubes in which the electrons proceed from the target to multiplier units arranged around the axis of the gun. In my said application, electromagnetic focusing and deflecting means are employed and the construction has operated very satisfactorily, but the weight of the tube unit and the power requirements are more than desired in certain uses.

It is an object of this invention to provide a storage tube of reduced weight and power requirements.

Another object of the invention is to arrange the electrodes and other parts so that electrostatic focusing and deflection of the cathode beam may be used with multiplier units arranged around and in the vicinity of the gun.

Other objects of the invention will appear in the following description, reference being had to the drawing, in which:

Fig. 1 is a longitudinal central section of a cathode ray tube employing the invention.

Fig. 2 is a partial section of the gun and deflecting electrodes with the surrounding shield, being taken on the line 2—2 of Fig. 3.

Fig. 3 is an end view of the parts shown in Fig. 2.

Fig. 4 is a section taken on the line 4—4 of Fig. 2.

Referring to the drawing, the tube comprises an evacuated glass or other suitable envelope 1 containing a gun at one end and a target 2 at the other end. The gun consists of an indirectly heated cathode 3 inside the grid 4 positioned adjacent the first anode 5. The grid has the usual aperture 6 and the end of the first anode adjacent the grid has a first aperture 7. The cathode, grid and first anode are of tubular metal construction, as usual. The first anode has a second defining aperture 8 adjacent the end remote from the grid (see Fig. 2). Close to and spaced from this end of the first anode is positioned the second anode 9, also of tubular metal construction, but having a cylindrical end 10 of reduced diameter. The grid, the first anode and second anode are mounted together by means of four mica strips 11 sectioned in solid block in Fig. 1. These have holes 12 therethrough. There should be two or more holes in each strip for each electrode. A thin metal ribbon 13 is placed lengthwise over the mica strips 11, over the cylinder of grid 4, and are welded through the holes 12 to the underlying cylinder. 55

2 Four similar metal strips 14 and 15 are welded through the holes 12 to the first and second anodes, respectively. The strips of the grid, first anode and second anode are, of course, spaced so as not to short these electrodes. All of the mica strips 11 are of such width as to center the electrodes within a shield tube 16, as will be made clear by Fig. 4.

5 A metal disc 17 is welded to the end of the second anode. This disc is of such diameter as to fit the inside diameter of shield tube 16, as the second anode and shield have the same applied potential and hence they need not be insulated from each other. The cylindrical end 10 and the disc 17 have appropriate apertures 18 for passage of the cathode beam.

10 A mica disc 19 fits inside shield tube 16 and against disc 17. A metal disc 20 is sandwiched between two mica discs 21 and 22 and these three discs are spaced from discs 17 and 19 as shown in Fig. 2. Metal discs 17 and 20 and mica discs 19, 21 and 22 have four holes 23 equally spaced around the circumference and four wires 24 snugly fit in these holes to position the discs circumferentially in respect to the second anode. The four wires are welded to the disc 17 and cross wires 25 are welded to the wires 24 against mica disc 19 and against mica discs 21 and 22 to hold them against metal discs 17 and 20, respectively. The metal discs 17 and 20 have eight holes 26 preferably arranged so that all the holes 23 and 26 are equally spaced around the circumferences. These eight holes are preferably larger than the holes 23, as indicated in Fig. 3. The mica discs 19, 21 and 22 have four holes 27 coaxial with and smaller than four of the holes 26 and wires 28, 29, 30 and 31, which may be smaller than wires 24, snugly fit the holes 27 and extend through the aligned holes of all five discs and sufficiently beyond to support the horizontally deflecting plates 32, 33 and are welded to wires 28, 29 and 30, 31, respectively. The mica discs 19, 21 and 22 likewise have four holes 34 coaxial with the remaining holes 26 in the metal discs 17 and 20 and four wires 35, 36, 37 and 38 snugly fit the holes 34 and extend through the aligned holes of the five discs. Vertically deflecting plates 39 and 40 are positioned between mica discs 19 and 21 and are welded to wires 35, 38 and wires 36, 37, respectively.

15 With the deflecting units assembled as described, the plates are individually insulated from each other and from the second anode and shield 16. Insulated wires 41, 42 and 43, 44 may extend between the shield tube 16 and the anode cylinder and be welded to appropriate ones of the sup-

porting wires of the deflection plates for supplying voltage thereto.

The grid and the first and second anodes are properly positioned and supported within the shield tube by the arrangement described and the cathode may be supported within the grid in any well-known manner. This is indicated in Fig. 1 by the cathode extending through insulation member 45 held in the end of the cylinder of grid 41. The shield 16 is flanged at 45a and is welded to the base of a cup-shaped gun mount 45b that may be supported in the envelope in any known way, for example, as disclosed in the application of Stanley V. Forgue, filed January 28, 1946, Serial No. 643,925 now Patent No. 2,441,315, issued May 11, 1948.

The usual wall coating 46 on envelope 1 extends from adjacent the end of shield tube 16 toward the target, as shown in Fig. 1. A focusing electrode 47 is positioned at the gun end of the wall coating and extends over the end of shield tube 16. First, second, third, fourth and fifth pin-wheel multiplier stages 48 to 52 and sixth multiplier stage 53 and collector 54 are positioned over the shield tube. These multiplier stages and collector are fully described in the application of Paul K. Weimer, filed September 16, 1944, Serial No. 554,494, now Patent No. 2,433,941, issued January 6, 1948, and reference is made thereto for information of all the details thereof. It may be said briefly, however, that the first to fifth stages each consist of a plurality of slanting vanes 55 somewhat like the blades of an electric fan. These are appropriately mounted in metal frames 56 in the front of which are mounted fine mesh screens 57 to shield the secondaries emitted by the vanes from the preceding potentials. It is preferable to make alternate dynodes with the blades slanting in opposite directions, as indicated in the partial section of stages 48 and 49. The final dynode in stage 53 may be a metal disc 58, as the secondaries emitted thereby are attracted directly to the collector 59, which may be a fine mesh screen like the screens 57. There may be any desired number of multiplier stages. The six stages shown are given merely by way of example. The target 2 may be an aluminum cup with a convex surface extending toward the gun. The cup may be anodized to form an oxide coating 60 on the convex side and a screen 61 is stretched over the oxide surface, as disclosed in my said application. A focusing ring 62 is placed adjacent the screen 61. The various electrodes may have suitable voltages, such as those given on the drawing. The negative and positive values are below and above ground, respectively, which is the potential of the screen 61. The voltages of the grid and first anode will, as generally understood, be adjusted for good focus on the target and the focusing ring electrodes 47 and 62 are adjusted for good focus on the first multiplier stage 48 of the secondary electrons emitted by target 2 upon impact of the beam thereon. The voltages of the various electrodes may be varied, but those given on the drawing will be found satisfactory.

The separate parts of the multiplier stages and collector may be assembled in frames in any way, for example like that disclosed in the application of Stanley V. Forgue, filed February 7, 1946, Serial No. 646,075, now Patent No. 2,460,381, issued February 1, 1949, and the multiplier, gun mount and focusing rings may be mounted as in the last-mentioned application or in any other way.

The horizontally and vertically deflecting plates may be connected to saw-tooth voltage generators, not shown, of appropriate line and frame scan frequencies, or to any other type of deflecting potentials required by the specific application.

My improved storage tube may be used whenever signals are to be stored and utilized at a later time. The storage time will, of course, depend upon the particular use of the tube and may vary from a fraction of a second to minutes, or even hours if desired. The change from storage condition to discharge or utilization condition may be by hand control or semi- or entirely automatic, as described in my application filed June 20, 1945, Serial No. 600,498, now Patent No. 2,454,410, issued November 23, 1948.

Before describing the way in which storage of signals is secured, it will first be advisable to explain the effect of the scan of the high velocity beam over the oxide target 60 with no signal being applied to the metal part 63 of the target cup 2. The potential of the oxide target surface 60 may happen to be positive, negative, or equal to the potential of the screen 61 and ground. For the moment, let it be assumed that the oxide coating is positive with respect to the screen. As the high velocity beam is scanned over the oxide coating, secondary electrons will be bombarded therefrom at a greater than unity ratio. It is desirable to have the secondary emission be two or three times as great as the number of electrons landing from the beam. Whether these secondary electrons, however, eventually escape from the oxide surface depends upon the relative potential between the oxide surface and the screen 61. Since it has been assumed that the oxide surface is positive relative to the screen, the secondaries will not escape but will return to the oxide surface. This means that the target surface is collecting the negative electrons of the beam and losing none from secondary emission. Therefore, the surface, upon impact of the beam, will be reduced to the potential of the screen 61. At this point just as many electrons will leave the oxide surface as are added to it from the beam. Scan of the beam over the oxide surface thus brings its potential to that of the screen through a net gain of electrons if it is positive to the screen, or through a net loss of electrons if it is negative thereto, and the elemental areas will stay at these relative potentials unless some extraneous potential is applied thereto.

While the improvement may be applied to various uses, the operation in a coherent pulse type of radar system will now be explained by way of example.

In the known coherent pulse radar system, the signal pulses are transmitted at the beginning of each line scan at the peak of the saw-tooth wave controlling this scan. Echoes from both moving and stationary objects are received and impressed on the dielectric target in certain phases of the scan, depending upon the distance of the objects from the transmitter-receiver. In most uses and in war work, particularly, the reflections or echoes from stationary or fixed objects, such as mountains, are not only of no interest, but they also clutter up the desired record of echoes from moving objects, such as airplanes, and make it difficult to determine which of the signals represent a moving object. With fixed objects the successive echoes arrive at the signal plate 63 always in the same phase of the

line scansion, because their distance from the transmitter-receiver does not vary and the amplitude is constant. The echo signals from moving objects, however, vary rapidly in amplitude, due to the well-known Doppler effect, and slowly change in phase due to their varying distance from the transmitter-receiver. This means that if an echo signal from a fixed object is impressed on the signal plate 63 when the beam in one scansion is on a certain elemental area of the target, the same signals from that same fixed object will be impressed on that elemental area and will have the same amplitude as the preceding signals. On the other hand, successive trains of echoes from moving objects will produce signals of varying amplitude when the beam is on a particular elemental area, because of the Doppler effect.

Suppose trains of echo signals from a mountain peak are constantly arriving while the beam is on the n th elemental area of a scanned line. The signal potential will be impressed on the entire signal plate 63 and the potential of the entire dielectric target 60 will be proportionally altered, say raised above the potential of screen 61. The n th area will therefore receive electrons from the beam in excess of emitted secondaries sufficient to bring the surface down to the potential of the screen. As the beam leaves the elemental area n , the signal potential ceases to be impressed on signal plate 63 and the potential of the dielectric surface, except area n , drops down to screen potential. The elemental area n drops in potential as far below the potential of the screen 61 as it was raised above it by the signal. Absence of signals will be assumed until the beam reaches the m th area, when an echo signal of positive potential, say, from a moving object, is impressed on signal plate 63. The potential of all areas of the surface of the target, including area n , will again be altered by the signal. When the beam leaves the m th elemental area, the entire dielectric drops down to the potential of screen 61 except the elemental areas n and m , which drop as far below the screen in potential as they were raised above it by their respective signals when the beam was on those areas. The signal is thus recorded on the scansion described.

On the next scansion by the beam, it will find elemental area n just as far below the screen potential as the signal potential of the wave train can raise it above that potential, because the signal is identical with that previously impressed on this area. Thus, the signal from the fixed object raises the potential of elemental area n up to the potential of screen 61. Therefore, the electrons from the beam landing thereon release secondaries in a one-to-one ratio to the beam electrons, so that the electron stream passing to the multiplier or to the collector screen is not modulated. When the beam reaches the m th area, the signal arriving from the moving object has a different amplitude, because of the Doppler effect. The beam finding the area m below the potential of screen 61 bombards a sufficient excess of secondary electrons from its surface to bring the potential back to that of screen 61. Thus, a signal is produced by an increase in the number of returning electrons.

It will thus be seen that with my invention the use of radar systems in operations over or near land surfaces has been enormously increased in effectiveness, due to the substantial elimination of signals from stationary objects, leaving only those from moving objects which it is desired to identify and locate.

In radar systems the antenna is usually rotated to survey the entire horizon for echoes from objects. Since the radiation pattern of present directional antennas has material and variable breadth, signals from objects will vary with the field strength of this pattern. The received signals from fixed objects in one scansion may therefore have different amplitudes from those of the previous scansion. Echoes from fixed objects thus tend to increase in amplitude from scansion to scansion as the center of the radiation pattern approaches them and to decrease from scansion to scansion as the center of the radiation pattern moves away from them. Since this change in amplitude is unidirectional over a number of radar cycles, the differences passed by the storage tube are all in the same direction. The output of the storage tube will therefore have a very slowly changing pattern of the differences, which can be removed by passing the signals through a second storage tube in cascade. That is, the output of one tube may be applied to the input signal plate of another tube. Since the small output pulses of the first tube will have substantially constant phase and amplitude for any two successive line scans for fixed objects, it will be apparent that the echoes from such objects will not produce signals. In the cascade arrangement, however, the echoes from moving objects will produce signals in the second tube, since they are of varying amplitude in the output of the first tube.

The improved storage tube may be used in various other ways where storage of information is desired. Signals may be impressed on the signal plate while the beam scans a predetermined pattern over the target. The signal and beam may then be shut off, leaving the information stored in the target. At any desired later time the beam may be turned on and, with no new signals impressed on the signal plate, scanned over the pattern so that the signal impressed during the first scansion will be taken off by the subsequent scansion. As is evident from the described method of operation, recorded signals may be combined with new signals, enabling one to use the tube for carrying out complex operations by suitable combinations of signals.

It will be apparent that when signals are recorded, the beam is modulated to the same extent as when the signals are taken off in a subsequent scansion, but in the opposite sense, and either or both modulations may be utilized when desired.

I claim:

1. A cathode ray beam storage tube comprising an evacuated envelope containing a gun, a target having a plurality of mutually insulated elemental areas, an electron multiplier between said gun and said target, a screen adjacent and in front of said target adapted to control secondary electrons bombarded from said target by said cathode ray beam, a plate capacitatively associated with said target for applying successive signal potentials simultaneously to all of the elemental areas of said target, means for electrostatically scanning said beam over said elemental areas and means for electrostatically focusing on said multiplier the electrons escaping from said target.

2. A cathode ray beam storage tube comprising an evacuated envelope containing a gun, a target having a plurality of mutually insulated elemental areas, an electron multiplier between said gun and said target, a screen adjacent and in front of said target adapted to control sec-

secondary electrons bombarded from said target by said cathode ray beam, a plate capacitatively associated with said target for applying successive signal potentials simultaneously to all of the elemental areas of said target, means for electrostatically scanning said beam over said elemental areas and means for electrostatically focusing the beam electrons on said target.

3. A cathode ray beam storage tube comprising an evacuated envelope containing a gun, a target having a plurality of mutually insulated elemental areas, an electron multiplier between said gun and said target, a screen adjacent and in front of said target adapted to control secondary electrons bombarded from said target by said cathode ray beam, a plate capacitatively associated with said target for applying successive signal potentials simultaneously to all of the elemental areas of said target, means for electrostatically scanning said beam over said elemental areas and means for electrostatically focusing the beam electrons on said target and the electrons escaping from said target on said multiplier.

4. A cathode ray beam storage tube comprising an evacuated envelope containing a gun, a target having a plurality of mutually insulated elemental areas, a screen adjacent and in front of said target adapted to control secondary electrons bombarded from said target by the cathode ray beam, a plate capacitatively associated with said target for applying successive signal potentials simultaneously to all of the elemental areas of the target, means for electrostatically scanning said beam over said elemental areas, a metal cylinder around said gun and said last mentioned means, an electron multiplier around said cylinder and means for electrostatically focusing on said multiplier the electrons escaping from said target.

5. A cathode ray beam storage tube comprising an evacuated envelope containing a gun, a target having a plurality of mutually insulated elemental areas, a screen adjacent and in front of said target adapted to control secondary electrons bombarded from said target by the cathode ray beam, a plate capacitatively associated with said target for applying successive signal potentials simultaneously to all of the elemental areas of the target, means for electrostatically scanning said beam over said elemental areas, a metal cylinder around said gun and said last mentioned means, an electron multiplier around said cylinder and means for electrostatically focusing the beam electrons on said target.

6. A cathode ray beam storage tube comprising an evacuated envelope containing a gun, a target having a plurality of mutually insulated elemental areas, a screen adjacent and in front of said target adapted to control secondary electrons bombarded from said target by the cathode ray beam, a plate capacitatively associated with said target for applying successive signal potentials simultaneously to all of the elemental areas of the target, means for electrostatically scanning said beam over said elemental areas, a metal cylinder around said gun and said last mentioned means, an electron multiplier around said cylinder and means for electrostatically focusing the beam electrons on said target and the electrons escaping from said target on said multiplier.

7. A cathode ray beam storage tube comprising an evacuated envelope containing a grid cylinder, a cathode supported within said grid cylinder, a

first anode cylinder spaced from said grid cylinder, a second anode cylinder spaced from said first anode cylinder, all said cylinders being coaxial, electrostatic orthogonally disposed deflecting plates, an open-end shield cylinder surrounding said cylinders and said plates, a target spaced from the open end of said shield cylinder, a screen adjacent the front surface of said target adapted to control secondary electrons bombarded from said target by the cathode ray beam, an electron multiplier positioned around said shield cylinder adapted to attract electrons escaping from said target and means for electrostatically focusing the escaping electrons on said multiplier.

8. A cathode ray beam storage tube comprising an evacuated envelope containing a grid cylinder, a cathode supported within said grid cylinder, a first anode cylinder spaced from said grid cylinder, a second anode cylinder spaced from said first anode cylinder, all said cylinders being coaxial, electrostatic orthogonally disposed deflecting plates, an open-end shield cylinder surrounding said cylinders and said plates, a target spaced from the open end of said shield cylinder, a screen adjacent the front surface of said target adapted to control secondary electrons bombarded from said target by the cathode ray beam, an electron multiplier positioned around said shield cylinder adapted to attract electrons escaping from said target and means for electrostatically focusing the beam electrons on said target and the escaping electrons on said multiplier.

9. A cathode ray beam storage tube comprising an evacuated envelope containing a grid cylinder, a cathode supported within said grid cylinder, a first anode cylinder spaced from said grid cylinder, a second anode cylinder spaced from said first anode cylinder, all said cylinders being coaxial, electrostatic orthogonally disposed deflecting plates, an open-end shield cylinder surrounding said cylinders and said plates, a target spaced from the open end of said shield cylinder, a screen adjacent the front surface of said target adapted to control secondary electrons bombarded from said target by the cathode ray beam, an electron multiplier positioned around said shield cylinder adapted to attract electrons escaping from said target and means for electrostatically focusing the beam electrons on said target.

10. A cathode ray beam storage tube comprising an evacuated envelope containing a grid cylinder, a cathode supported within said grid cylinder, an anode cylinder spaced from said grid cylinder, said cylinders being coaxial, electrostatic deflecting plates providing orthogonal deflection, an open-end shield cylinder surrounding said other cylinders and plates, a target spaced from the open end of said shield cylinder, a screen adjacent the front surface of said target adapted to control secondary electrons bombarded from said target by the cathode ray beam, an electron multiplier positioned around said shield cylinder adapted to attract electrons escaping from said target and a pair of spaced electrostatic rings between said target and said multiplier and outside said shield cylinder for focusing the escaping electrons on said multiplier.

11. A cathode ray beam storage tube comprising an evacuated envelope containing a grid cylinder, a cathode supported within said grid cylinder, a first anode cylinder spaced from said grid cylinder, a second anode cylinder spaced

from said first anode cylinder, all said cylinders being coaxial, electrostatic deflecting plates providing orthogonal deflection, an open-end shield cylinder surrounding said other cylinders and plates, a target spaced from the open end of said shield cylinder, a screen adjacent the front surface of said target adapted to control secondary electrons bombarded from said target by the cathode ray beam, an electron multiplier positioned around said shield cylinder adapted to attract electrons escaping from said target and a pair of spaced electrostatic rings between said target and said multiplier and outside said shield cylinder for focusing the escaping electrons on said multiplier.

12. A cathode ray storage tube comprising an evacuated envelope containing a grid cylinder, a cathode supported within said grid cylinder, an anode cylinder spaced from said grid cylinder, said cylinder being coaxial, electrostatic deflecting plates, a plurality of insulation strips extending axially of said cylinders and outside thereof, means for securing said insulation strips to said cylinders, a shield cylinder surrounding the other cylinders and said plates, said insulation strips being sufficiently wide to engage said shield cylinder and space the two first-mentioned cylinders therefrom and means for insulatingly attaching said deflecting plates to said anode in

spaced relation from each other and from said shield cylinder.

13. A cathode ray storage tube comprising an evacuated envelope containing a grid cylinder, a cathode supported within said grid cylinder, a first anode cylinder spaced from said grid cylinder, a second anode cylinder spaced from said first anode cylinder, all said cylinders being coaxial, electrostatic deflecting plates, a plurality of insulation strips extending axially of said cylinders and outside thereof, means for securing said insulation strips to said cylinders, a shield cylinder surrounding the other cylinders and said plates, said insulation strips being sufficiently wide to engage said shield cylinder and space the three first-mentioned cylinders therefrom and means for insulatingly attaching said deflecting plates to said second anode in spaced relation from each other and from said shield cylinder.
